(57) **CLAIM**

The ornamental design for a medical device, as shown and described.

DESCRIPTION

U.S. patent application Ser. No. 29/639,289 is related to, and incorporates by reference, the entire disclosures of U.S. application Ser. Nos. 29/639,287, 29/639,249, 29/639,258, 29/639,241, and 29/639,259, all filed Mar. 5, 2018, the entire disclosures of which are hereby incorporated herein by reference.

FIG. 1 is a front perspective view of a medical device showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a rear perspective view thereof; and,

FIG. 9 is another front perspective view thereof, the front perspective view of FIG. 9 being similar to the front perspective view of FIG. 1 but for the depiction in broken lines of unclaimed environmental structure in FIG. 9.

The broken lines in FIGS. 1-8 depict portions of the medical device that form no part of the claimed design.

The broken lines in FIG. 9 depict portions of the medical device that form no part of the claimed design, and also depict environmental structure that forms no part of the claimed design.

1 Claim, 9 Drawing Sheets
